AIR CONDITIONING SYSTEM

Norman Passur, Oakland, Calif.

Application October 25, 1937, Serial No. 170,817

6 Claims. (Cl. 62—6)

The present invention relates to air conditioning systems of the type in which ice is used as the cooling agent and water as the circulating cooling medium.

The principal object of the invention is to provide increased efficiency in the use of ice, whereby less ice is required to produce a given amount of cooling. A second object is to prevent unnecessary waste of water. Still further objects and advantages of the invention will become apparent in the following specification which should be read with the understanding that the form, construction and arrangement of the various parts may be varied within the limits of the claims hereto appended, without departing from the spirit of the invention.

The system has been designed primarily for use in railway cars, and is so described herein. It will be apparent, however, that the system may be used in other applications without material change.

The figure of the drawing herein is a diagram illustrating the relative arrangement of and connections between the various elements constituting the entire system.

The reference numeral 1 designates an ice tank, which, in railway car installation, is positioned preferably beneath the floor 2 of the car. A grate or rack 3 is provided in the tank 1 upon which blocks of ice 4 are supported, and below said grate the bottom 5 of said tank slopes downwardly toward an outlet pipe 6 which leads to a water storage tank 7. Both the ice tank 1 and the water tank 7 contain water during the operation of the system, the maximum level of said water, as indicated by the broken line 8, being determined by an overflow outlet 9 in the upper portion of the water tank.

The ice tank 1 has a second outlet pipe 10 which leads through a check valve 11 to a water circulating pump 12, driven preferably by an electric motor 13. The discharge pipe 14 of said pump conducts the cold water to an absorber preferably in the form of a cooling coil 15, hereinafter referred to as the auxiliary cooler. From said absorber the water returns through a pipe 16 to the ice tank 1.

The water storage tank 7 has an outlet pipe 17 leading from its lower portion, which conducts the water through a check valve 18 to a second pump 19 driven preferably by an electric motor 20. The discharge pipe 21 of said second pump 19 leads to an absorber preferably in the form of a cooling coil 22, hereinafter referred to as

the pre-cooler, from which the water returns through a pipe 23 to the water storage tank 7.

A branch 24 of the pipe 21 leads to a spray nozzle 25 in a washer 26. The water sprayed within said washer is caught by a pan 27 in the bottom thereof, and returns to the water storage tank 7 through a pipe 28. The washer 26 thus functions as an absorber in parallel with the coil 22. Said coil 22 may, if desired, be omitted, the entire pre-cooling effect being provided by the washer 26.

The pre-cooler 22, the washer 26, and the auxiliary cooler 15 are arranged in a unit structure, preferably above the floor 2 of the car, so that air is drawn through them by a fan 29. A steam radiator 30, through which steam may be passed from suitable steam pipes 31 when heating rather than cooling is desired, is included in the system. Air enters through the pre-cooler 22, thence passes through the washer 26 where it is cleaned, humidified and deodorized by the water spray, thence through the heating radiator 30, thence through the auxiliary cooler 15, and is again discharged into the car by the fan 29. The path of the air is indicated by the large broken line arrows in the figure.

Separate thermostats 32 and 33 suitably positioned within the car, control the respective pump motors 13 and 20. The electric circuits necessary to operate and control said motors are common and well known in the art, and are not illustrated in the diagram, the connecting lines 34 and 35 between the thermostats and said motors merely indicating that each motor is individually controlled by its own thermostat.

In operating the apparatus, ice is placed within the tank 1, and sufficient water is added to permit circulation in the two systems, without necessarily filling both the ice tank 1 and the water storage tank 7. The thermostat 33, controlling the pre-cooler pump 19, is set to operate at slightly lower temperatures than the thermostat 32 which controls the auxiliary cooler pump 12. Therefore, as the temperature of the car rises, the pre-cooler pump 19 begins to operate first circulating water from the storage tank 7 through the pre-cooler 22 and washer 26, said water returning to said storage tank. Under mild weather conditions, such operation of the pre-cooler and washer are usually sufficient to maintain the temperature of the car within the desired limits, in which case the auxiliary cooler pump 12 is not operated, and no water circulates through the ice tank 1. Under these conditions, the ice melts comparatively slowly, and no water

is lost through the overflow 9 until sufficient melting has occurred to fill both tanks.

However, if the temperature of the car continues to rise during operation of the pre-cooler 5 and washer, the thermostat 32 starts the auxiliary cooler pump 12, which circulates water from the ice tank 1 through the auxiliary cooler 15 and back to said ice tank. The auxiliary cooler 15 being larger than the pre-cooler 22, and the water 10 therein being circulated directly over the ice, the temperature of the car is rapidly lowered to such a point that the thermostat 32 shuts off the auxiliary cooler pump 12. The pre-cooler pump 19 continues to operate however until the car 15 temperature falls still further.

When the auxiliary cooler is operating, the ice melts more rapidly, raising the water level, causing cold water to flow from the ice tank to the water storage tank, and discharging warmer 20 water from the outlet 9. This reduces the temperature of the water in said storage tank, and increases the cooling effect obtained from the pre-cooler.

It will be seen that the invention contemplates 25 the use of two functionally independent circulation systems, one containing both ice and water, and having greater cooling capacity, and the other containing water only, and having less cooling capacity. The water in the second or pre-cooling system is supplied initially and replenished more or less continuously from the first system, and to that extent is cooled by the ice. The water in the pre-cooling system operates at a 30 higher temperature than the water in the auxiliary cooling system, and since the only water discharge for both systems is through the overflow 9 of the pre-cooling system, the water lost through said discharge is necessarily at comparatively high temperature, i. e. a temperature only slightly 35 below the air temperature maintained in the car. Thus the greatest possible efficiency and the least possible loss of water are obtained.

The pre-cooling system operates through a much longer cycle than the auxiliary cooling system. As before stated, under conditions of mild 45 temperature, the auxiliary system may not operate at all, but the pre-cooling system will operate almost continuously. This provides almost continuous circulation and washing of the air in the car, removing odors and dust therefrom, with very little melting of ice and loss of water.

It will be apparent that certain elements of the two systems may be combined without affecting the independent functioning of said systems. 50 Thus for example, a single pump with a suitable selective control valve may be substituted for the two separate pumps hereinbefore described, and a single absorber, with suitable connections from and to the two tanks, may be substituted for the two separate absorbers. Such variations, being obvious to those skilled in the art, have not been 55 illustrated herein.

I claim:

1. In an air conditioning system, a tank containing both ice and water, a second tank containing water, means for supplying the second tank with water from the first tank, an absorber connected with the first tank, a second absorber connected with the second tank, means for circulating the water from said tanks independently through their respective absorbers and returning 65

it independently to said tanks, and means for passing the air to be conditioned over said absorbers.

2. In an air conditioning system, a tank containing both ice and water, a second tank containing water, means for supplying the second tank with water from the first tank, an absorber connected with the first tank, a second absorber connected with the second tank, means for circulating water 10 from the first tank through the first absorber, and means for circulating water from the second tank through the second absorber and said washer, all of said water being returned independently to the respective tanks, and means for passing 15 air over said absorbers and through said washer.

3. In an air conditioning apparatus, a closed circulating system including an absorber and storage means containing ice and water, a second closed circulating system including a second absorber of less capacity than the first absorber and storage means containing water, means for transferring cold water from the first system to the second system, means for circulating the water in said systems, means for passing the air to be conditioned over said absorbers, and means responsive to the temperature of the conditioned air for selectively controlling said circulation, the first system operating at higher air temperatures than the second system.

4. In an air conditioning apparatus, a closed circulating system including an absorber and storage means containing ice and water, a second closed circulating system including a second absorber, a washer, and storage means containing water, means for passing the air to be conditioned over said absorbers and through said washer, means for transferring cold water from the first system to the second system, means for circulating the water in said systems, and means responsive to the temperature of the conditioned air for selectively controlling said circulation, the first system operating at higher air temperatures than the second system.

5. In an air conditioning apparatus, two closed water circulating systems, each system including heat absorbing means and one system including means for storing ice, a connection between said systems for transferring cold water supplied by the melting of said ice in one system to the other 50 system, means for discharging warmer water from said other system as said melted ice water is supplied to it, means for circulating the water in each system, means for separately controlling the circulation in said systems, and means for 55 passing the air to be conditioned over said heat absorbing means.

6. In an air conditioning system, a tank containing both ice and water, a second tank containing water, a connection between said tanks 60 positioned to supply cold water from the lower region of the first tank to the second tank, an absorber connected with the first tank, a second absorber connected with the second tank, means for circulating the water from said tanks independently through their respective absorbers and returning it independently to said tanks, and means for passing the air to be conditioned over 65 said absorbers.
